RETRIEVING TOOL FOR WELL BORES

George W. Walton, Dallas, Tex., and Donald L. McCarty, Milwaukee, Wis., assignors to Ideco, Inc., a corporation of Ohio

Application March 9, 1954, Serial No. 415,034

4 Claims. (Cl. 166—65)

This invention relates to a retrieving tool for well bores and particularly to a magnetic pick up tool adapted for use in removing paramagnetic objects or foreign bodies such as broken parts of drilling bits from the bottom of the bore.

In order to facilitate the operation of such magnetic retrieving tools, it is desirable to eject fluid under pressure (such for example, as drilling "mud") into the bottom of the bore so that a fine suspension of solids is produced in that region to obviate interference by sand or other earthy material with the contacting of objects sought to be removed by the magnet. This usually has been accomplished in the past by ejecting such fluid away from the magnet through the most intense portion of the magnetic field so that the pressure of the ejected fluid tends to retard the desired contact of the foreign bodies with the magnet and the desired adherence of such objects thereto.

The present invention overcomes the foregoing objections by providing fluid discharge passages which eject fluid into the bore through regions of weakest magnetic intensity. At the same time, return fluid flow passages from the bottom of the well bore through the tool are so arranged that such return flow is toward the magnet and is through regions of greatest magnetic intensity thus assisting in bringing the foreign bodies into contact with the magnet. We further arrange to provide pockets within such return flow passages by interposing passaged non-magnetic barriers. These pockets receive and assist in retaining smaller objects picked up by the tool.

It is an important object, therefore, of the present invention to provide a magnetic retrieving tool for well bores which is so arranged that the discharge of drilling fluid therefrom, while achieving the desired results of producing a suspension of fine solids within the bottom of the well bore, does not interfere with, or oppose, the desired action of the magnet.

It is another important object of this invention to provide a magnetic retrieving tool for well bores which has return fluid flow passages so arranged that the return flow of drilling fluid enhances and assists the desired magnetic action.

It is a further object of such invention to so arrange the return flow passage as to provide a pocket for the reception and retention of smaller objects picked up during the operation of the tool.

Other and further objects of the present invention will be apparent from the disclosures in the following specification and the accompanying drawings.

The invention (in a preferred form) is shown on the drawings and hereinafter more fully described.

On the drawings:

Fig. 1 is a central longitudinal section taken through a retrieving tool embodying the principles of the present invention; and

Fig. 2 is a bottom plan view of the tool shown in Fig. 1. As shown on the drawings:

In the specific embodiment of this invention chosen for purposes of illustration herein, the reference numeral 10 indicates a head member which is provided with an internally threaded socket 11 adapted for reception of a correspondingly externally threaded drill pipe 12 by which the tool is moved into and out of the well casing to the bottom of the well bore and through which fluid under pressure, such, for example, as drilling "mud," is introduced into the bottom of the bore in a manner to be described hereinafter. The head member 10 which is made of steel is provided with an annular horizontal shoulder at an enlarged lower portion thereof, such shoulder being designated by the reference numeral 13. The bottom of the recess or socket 11 communicates with the lower face 15 of the head member 12 for passage of fluid under pressure through a plurality of passageways 14, two of which are shown in full lines in Fig. 1.

Abutting the shoulder 13 is the upper end of a cylindrical casing member 15 made of stainless steel or other non-magnetic strong metal or metal alloy. The casing 15 is secured to the head member 10 by welding as shown at 16 and by engagement of the upper end of the inner wall of the casing with a cylindrical portion 17 on the lower end of said head member.

In firm contact with, and if desired suitably welded to, the lower face of the head member 10 are a pair of permanent magnets 18 which may be of generally semi-cylindrical cross-section and which are preferably symmetrically arranged with reference to the axis of the cylindrical casing 15 so that an annular passageway 19 is provided between the outer faces of said magnets and the inner face of the cylindrical wall 15. The magnets 18 are preferably composed of an alloy of aluminum, nickel and cobalt of high magnetic retentivity and as shown in Fig. 1 have their inner parallel faces spaced from each other to form a passageway therebetween and also to provide the required gap between the poles of the magnet at the lower end of the casing, the magnetic circuit at the upper end of the casing being closed by the head member 10. The inner parallel faces of the magnets 18 are preferably covered by non-magnetic stainless steel plates 18a welded to the top side of the pole shoes 24 and extending to the head member 10 and welded thereto. These plates seal off the annular fluid supply passage 19

from the return fluid passage 20 and also permit of welding the space bar 21 in position without affecting the magnetic properties of the permanent magnets 18. The gap or passageway between the magnet members 18 is designated generally by the reference numeral 20 and this gap or passageway is preferably closed by a passaged spacer or bar 21 of stainless steel or other non-magnetic material. The bar 21 is provided with a plurality of apertures or small passageways 22 which afford a path for a return flow of drilling fluid in a manner to be described hereinafter. The passageway afforded by the gap 20 communicates fluid discharge through the lower portion of the head 10 by way of a plurality of passages 23 which are so arranged as not to intersect the fluid inlet passages 14.

In order to assure of high magnetic intensity, the magnets 18 are provided with pole pieces or plates in the form of a divided annular ring 24 having a transverse opening or gap 25 communicating with the gap or return passageway 20 beneath the apertured spacer bar 21. The annular pole pieces or plates 24 tightly engage the inner wall of the casing 15 near the lower end thereof and spaced inwardly therefrom for a purpose to be described hereinafter and where the plates 24 bridge the bottom of the annular recess 19, the said plates are provided with a plurality of passageways or apertures 26 which, in effect, are discharge passages or jets for the discharge of drilling

fluid introduced through the passages 14 and the annular passage 19 into the bottom of the well bore.

The pole pieces or plates 24 are preferably made of magnetic steel of high permeability to assure of high concentration of magnetic lines of force at the opposed working poles of the magnet.

The pole pieces or plates 24 may be secured in association with the casing 15 by welding or in any suitable manner, it being the purpose and intent of this invention that the assembled parts be held in rigid association.

As will be noted from an examination of Fig. 1 the lower end of the casing 15 extends somewhat below the lower face of the pole pieces. This lower end portion of the casing 15 is threaded as at 27 for reception of a guide collar, mill or shoe (the use of which is optional). By having the casing 15 extend downwardly as shown for reception of such guide collar, mill or shoe, it is obvious that magnetic leakage will be minimized.

In operation, the retrieving tool of this invention is lowered into the well at the lower end of a string of drill pipes in the same manner as would be the case with a drilling tool affixed to such drill pipe. Fluid under pressure is pumped through the drill pipe into the socket 11 and head 10 and thence through the passages 14 into the annular passage 19, whence it is discharged through the jets or passages 26 into the bottom of the well bore to maintain the required fluid suspension at that region. If the lower edges of the casing 15 are not directly against the bottom of the well bore, fluid so discharged to a large extent returns outside of the casing 15 in an upward direction. If, however, the lower edges of the casing 15 or of a guide shoe or the like attached thereto rest rather tightly against the bottom of the well bore, then the return flow is largely through the passages 22 in the apertured spacer 21 and thence upwardly through the space 20 and out through the passages 23.

Under intermediate conditions a portion of the return flow of fluid discharged through the passages 26 is outside of the casing 15, while a portion thereof is back through the passage 20 and outlet passages 23. It will be appreciated that the region of greatest intensity of magnetic flux and consequently of greatest attraction to objects to be retrieved by the magnet is in the area across the poles of the magnets 18 at the pole plate 24. Consequently, by reason of the arrangement for fluid discharge which I have prepared, attraction of objects at this region is not retarded by the outwardly flowing fluid under pressure. On the other hand, the return flow toward that region enhances the movement of objects toward the magnet and furthermore smaller objects will be carried by that return flow and the magnetic attraction into the pocket between the lower ends of the magnets 18 and the apertured spacer 21, the apertures in that spacer being sufficiently small so that the objects will not move therethrough. Since the vertical walls of the pocket are in a region of relatively high magnetic density, paramagnetic objects moved into the pocket by fluid flow and magnetic attraction will be held in the pocket by the latter.

By reason of the arrangement of this invention, it is possible to discharge the required fluid under pressure into the bottom of the well bore in such a way as not to interfere or impede the action of the magnet and the return flow of that fluid is so arranged as to enhance such action.

In this specification we have shown and described a preferred embodiment of our invention by way of example only, it being understood that any arrangement of the magnet and casing whereby the outward flow of fluid under pressure is in a region relatively remote from the region of greatest magnetic intensity and wherein the return flow of such fluid is through that region, may fall within the scope of this invention.

While the tool described herein is primarily intended for the removal of paramagnetic objects from well bores, it may also be effectively used for retrieving such objects from horizontal rock drill bores or other bores bearing varying angular relationship to the datum surface. Although primarily intended for use with a circulating fluid, the tool of this invention may also be used without such circulation in a "dry hole" where it is possible to bring the tool into position to directly attract and hold the paramagnetic objects to be removed.

We claim as our invention:

1. In a magnetic retrieving tool for well bores, a head member having an internal socket formed therein in the upper portion thereof through which fluid under pressure is introduced into a well bore, a cylindrical casing depending from said head member and forming a chamber, said head member having a lower face extending across the upper end of said chamber, a pair of permanent magnets in said chamber, said magnets being semi-cylindrical in cross-section and being symmetrically arranged to form an axial passage in said chamber, means supporting said pair of permanent magnets at said lower face, said pair of magnets being spaced radially inwardly of said casing to form together with said casing an annular passage in said chamber spaced outwardly of said axial passage, said head member having fluid-conducting means formed therein extending between said internal socket and said annular passage to eject fluid through the tool, and additional fluid-conducting means extending from said axial passage through said head member to the outside of said head member so the flow of return fluid is through the tool at the region of greatest magnetic intensity.
2. In a magnetic retrieving tool for well bores, a head member having an internal socket formed therein in the upper portion thereof through which fluid under pressure is introduced into a well bore, a cylindrical casing depending from said head member and forming a chamber, said head member having a lower face extending across the upper end of said chamber, a divided annular ring having a transverse opening and tightly engaging the inner wall of said casing near the lower end of said chamber, a pair of permanent magnets supported by said divided annular ring in said chamber at said lower face, said magnets being spaced radially inwardly of said casing and being spaced from one another to form an axial passage between said magnets and an annular passage concentrically outwardly thereof, said head member having fluid-conducting means formed therein extending between said internal socket and said annular passage to eject fluid through the tool and having additional fluid-conducting means extending from said axial passage to the outside of said head member so the flow of return fluid is through the tool at the region of greatest magnetic intensity.
3. In a magnetic retrieving tool as defined in claim 2, an apertured spacer bar in said axial passage above the lower end of said pair of permanent magnets to form a pocket receiving small articles washed thereinto by the flow of return fluid.
4. In a magnetic retrieving tool as defined in claim 3, said magnets having inner parallel confronting faces and having plates of non-magnetic material fastened thereto.
